Patented June 5, 1917.

UNITED STATES PATENT OFFICE.

ROY E. REED, OF RIPON, WISCONSIN.

DIMMING DEVICE.

1,228,477.

Specification of Letters Patent. Patented June 5, 1917.

Application filed November 8, 1916. Serial No. 130,249.

To all whom it may concern:

Be it known that I, ROY E. REED, a citizen of the United States, and a resident of Ripon, in the county of Fond du Lac and State of Wisconsin, have invented certain new and useful Improvements in Dimming Devices; and I do hereby declare that the following is a full, clear, and exact description thereof, reference being had to the accompanying drawings, and to the letters of reference marked thereon, which form a part of this specification.

This invention relates to a dimming device for regulating electric lights, such as head-lights and other lights, more especially for use in connection with the lights of automobiles, and consists of the matters hereinafter described and more particularly pointed out in the appended claims.

20 The object of the invention is to produce a dimming device of the kind described, which is of simple and economical construction; which is readily and easily applied to any motor vehicle, either in the initial construction of such vehicle or at any time afterward; and which includes a controlling member conveniently placed near the steering wheel and preferably near the usual engine controlling arms located thereon.

30 The advantages of my improvement will appear as I proceed with my specification.

In the drawings:

Figure 1 is a view representing a side elevation of the steering post of an automobile, with my improved dimming device attached to it, and with the head-lights, battery and electric conductors and other connections indicated diagrammatically.

Fig. 2 represents a longitudinal, central 40 section through the dimming device on an enlarged scale.

Fig. 3 represents a top plan view of the same.

Fig. 4 is a view representing on a still 45 larger scale, a transverse section through the device in a plane indicated by the line 4—4 of Fig. 2.

My improved dimming device comprises in general a resistance unit or member which 50 is interposed in the electric circuit that supplies the head-lights or other lights of the vehicle, and a controlling member, associated with the resistance unit, in such manner that resistance, variable at the will of the

operator, may be cut into the said electric 55 circuit to vary the intensity of the lights.

Referring now to that embodiment of my invention illustrated in the drawings:—10 indicates the steering post and 11 the steering wheel of an automobile or other motor vehicle. 12, 12 indicate the lights, in this case the head-lights of the vehicle; 13 indicates the battery or other source of current for the supply of the lights; and 14, 15 indicate the line wires leading from said battery 55 to the lamps.

16 indicates the dimming device as a whole. Said device has an inclosing casing consisting of an elongated, tubular barrel 17 and of top and bottom end caps 18, 19. Within the barrel 17 is placed a helical coiled wire 20, made of resistance material and constituting the resistance unit of the device. Insulation tubes 21, 22 are placed, the first without the coil, to insulate it from the barrel, and the second, within the coil to insulate the coil from the parts within the barrel. The inner insulation tube 22 is provided with a longitudinal slot 23, which extends longitudinally of the barrel and which uncovers the coil throughout the length and width of said slot and exposes the sections of said coil to engagement by a switch member presently to be described.

The outer sleeve 21 extends the full 85 length of the barrel. The inner insulation sleeve 22 extends to the end of the barrel at the top, but terminates short of the bottom end of the barrel. The top ends of the insulation sleeves are held apart and in proper spaced relation, by means of a spacing collar 25. In the bottom end of the barrel within the outer insulation sleeve 21, is located an insulation plug 26, which has a reduced end 27 which engages within and gives support to the bottom end of the inner insulation sleeve. The insulation plug 26 is attached by screws or in any other convenient manner, to a flat ring 28 resting on the bottom cap 19.

The bottom cap 19 is apertured and is provided with a tubular sleeve or extension through which a cable 29 containing the line wires 14 is introduced into the barrel. An insulation thimble 30 is interposed between the sleeve and the cable.

One section of the line wire 14 is connected to the bottom end of the resistance

coil 20, being extended up through a passage 31 in the insulation plug 26. The other section of the line wire is electrically connected to the metal disk 28, thus placing it 5 in circuit with the barrel. The top end of the resistance coil is extended, as indicated at 32, through a hole in the inner insulation sleeve 22 and bent up in such fashion as to fix that end without connecting it electrically to the barrel.

Within the barrel and located with its axis coaxial with the longitudinal, central axis of the barrel, is placed a rotative shaft 33. Said shaft has bearing at its bottom end 15 in a recess 34 in the top of the insulation plug 26, and at its top end in an aperture or opening 18* in the cap 18. The shaft is held within the barrel by means of a coiled expansion spring 35, which is interposed between the top cap 18 and a pin 36 fixed to the shaft. An arm 37 is fixed to the end of the shaft which projects beyond the barrel. Within the barrel there is fixed to the shaft, a spring metal toothed comb 38. 25 The teeth 39 are blunted or rounded and are sufficiently long that they will bear closely against the surface of the inner insulation sleeve, as the shaft 33 is rotated in either direction, and, when they are brought 30 into radial alinement with the spiral slot 23, will extend through said slot and engage a section or sections of the resistance coil 20. The metal comb as shown is fixed between two sections of the shaft. Preferably, the 35 shaft 18 is split longitudinally in the plane of its longitudinal axis and the comb is fixed between the two parts which are held together by pins or rivets 40.

The toothed metal comb 38 and the slot 40 23 in the insulation sleeve 22 are so correlated as to form (the slot, as illustrated being spiral and the comb being parallel to its axis of revolution), that as the comb is revolved about the axis of the casing, the 45 teeth 39 of the comb will be caused in succession to come into radial alinement with the slot 23 and to engage through said slot with a section of the resistance coil. The comb may thus be caused to bring any desired number of sections of the resistance coil into the circuit, thus varying the resistance therein.

In order to make the operation of the teeth of the comb smooth and easy as they 55 pass from the inner surface of the inner insulation tube to engagement through the slot with the resistance coil, the edges of the slot are chamfered or skived, as clearly shown in Fig. 4.

60 The top surface of the cap 18 is preferably provided with a graduated arc 41 with which is associated a pointer 42, carried by the hub of the arm 37. Pins 43, 44 are fixed at the top of the cap in arcuate alinement 65 with the path of movement of the pointer

41, and act as stops to limit the movement of the arm 37. The arcuate distance between the pins 43, 44 is made greater than the arc through which the spiral slot 23 is continued. Thus, when the arm is swung to move the pointer 42 into engagement with the pin 43 (in the example of the construction illustrated) the circuit will be broken, since the comb will be swung beyond a position in which any of its teeth can engage 70 through the slot 23 with the resistance coil 20. When the arm is swung to carry the pointer toward the other pin, the full length of the resistance coil will be brought at first into the circuit, and gradually, as the pointer 80 approaches the other pin, the length of said resistance coil in the circuit will be reduced. The light is thus, in this movement of the arm, put on gradually and finally brought to complete brilliancy, which it reaches when 85 the pointer strikes the other pin 44 and thus eliminates the entire length of the resistance coil.

I claim as my invention:

1. A dimming device adapted to be interposed in the line circuit of electric lights for motor vehicles and the like, comprising a casing, a resistance coil placed within and insulated from said casing, an insulating sleeve within said casing having a slot extending longitudinally of the casing, and a brush device having teeth adapted to expand radially in said casing and to project through said slot into engagement with said resistance coil, said brush and casing being 90 rotative, the one with respect to the other and said slot and brush being correlated in form to bring the teeth of the brush in successive alinement with said slot in said rotative movement.

2. A dimming device adapted to be interposed in the line circuit of electric lights for motor vehicles and the like comprising a casing, a resistance coil placed within and insulated from said casing, an insulating sleeve within said casing having a spiral slot extending longitudinally of the casing, and a brush device mounted in said casing, said brush and casing being rotative, the one with respect to the other, and said brush device having radially expansible teeth adapted to be brought by said rotative movement into engagement through said slot with successive sections of said resistance coil.

3. A dimming device adapted to be interposed in the line circuit of electric lights for motor vehicles comprising a casing, a resistance coil placed within and insulated from said casing, an insulating sleeve fixed in said casing within said coil and having a spiral slot which extends longitudinally of the casing, a brush device rotatively mounted in said casing, said brush device having alined flexible teeth which are adapted to be brought into engagement with successive sec-

tions of said coil by engagement with that part of said coil exposed by said spiral slot when said brush device is rotated and means without said casing for rotating said brush device.

4. A dimming device adapted to be interposed in the line circuit of electric lights for motor vehicles comprising a casing, a helical resistance coil within and insulated from said casing, an insulating sleeve within said coil and having a spiral slot extending longitudinally of said casing, a shaft journaled in and arranged coaxially of said casing, a brush member fixed to said shaft, said brush member having aligned flexible teeth which are adapted to be brought into engagement with successive sections of said coil by engagement with that part of said coil exposed to the teeth by said spiral slot when said shaft is rotated and a lever fixed to said shaft without the casing for rotating said shaft and brush.

5. A dimming device adapted to be interposed in the line circuit of electric lights for motor vehicles comprising a casing, a helical resistance coil within said casing, an insulating sleeve between said coil and casing, an insulating plug in one end of said casing and having a metallic contact member in engagement with said casing, an insulating sleeve within said coil and bearing at one end on said plug and being fixed at its other end to said first mentioned insulating sleeve, said second mentioned sleeve having a spiral slot extending longitudinally of the casing, said coil being fixed at one end in said insulating plug and at its other end to said slotted insulating sleeve, a shaft coaxial within said casing and having rotative bearing at one end in said insulating plug, a brush device fixed to said shaft, having longitudinally spaced flexible teeth which are adapted to be brought into engagement with successive sections of said coil by en-

gagement with that part of said coil exposed to the teeth by said spiral slot when said shaft is rotated and a handle fixed to said shaft without the casing for rotating said shaft.

6. A dimming device adapted to be interposed in the line circuit of electric lights for motor vehicles comprising a tubular casing closed at its ends by caps, a helical resistance coil in said casing, an insulating sleeve between said casing and said resistance coil, an insulating plug in one end of said casing having a metallic contact member engaging the adjacent cap, an insulating sleeve within said resistance coil, and bearing at one end on said insulating plug, said second mentioned sleeve having a spiral slot extending longitudinally of the casing, said coil being fixed at one end in said insulating plug and at its opposite end to the other end of said second mentioned insulating sleeve, a shaft coaxial within said casing bearing at one end in said insulating block and at its other end in the other end closing cap, a brush device fixed to said shaft, said brush device having longitudinally spaced flexible teeth which are adapted to be brought into engagement with successive sections of said coil by engagement with that part of said coil exposed to the teeth by said spiral slot when said shaft is rotated, a spring surrounding said shaft between said top closing cap and said brush and a handle fixed to said shaft without the casing for rotating the shaft.

In testimony, that I, claim the foregoing as my invention I affix my signature in the presence of two witnesses, this 6th day of November A. D. 1916.

ROY E. REED.
